Inventor
F. F. Weber,

By *Clarance A. O'Brien*,
Attorney

UNITED STATES PATENT OFFICE.

FRANK F. WEBER, OF YORKVILLE, ILLINOIS.

PIPE CLEANER.

Application filed October 27, 1925. Serial No. 65,163.

This invention relates generally to smoking pipes, and has more particular reference to a means that is associated with the pipe for enabling the cleaning of the bowl of the 5 same after each smoke in order that the interior of the bowl will not become caked with nicotine and tobacco particles, which is now the case after continued use of the pipe.

The primary object of the invention is to 10 provide a cleaner that is associated permanently with the pipe for permitting of the cleaning of the bowl thereof, without the agency of any separate tool or implement.

A further object of the invention is to 15 provide a cleaner of this character that may be associated with a pipe of conventional form without modifying the construction of the pipe to any considerable extent and that may be also so constructed as to be associated 20 with pipes that carry a removable bowl construction.

With the foregoing and other objects in view as the nature of the invention will be better understood, the same comprises the 25 novel form, combination and arrangement of parts hereinafter more fully described, shown in the accompanying drawing and claimed:

In the accompanying drawing, wherein 30 like reference characters indicate corresponding parts throughout the several views:

Figure 1 is a fragmentary sectional view of a conventional form of pipe with which is associated my novel cleaner.

Figure 2 is a top plan view of a pipe 35 equipped with a removable bowl construction within which bowl construction is disposed my novel cleaner, and

Figure 3 is a longitudinal section through 40 Figure 2, a portion of the pipe construction being shown in elevation.

First having reference to Figure 1, the pipe shown therein includes a bowl 5 and stem 6, and in order to adapt this form of 45 pipe to a cleaner constructed in accordance with this invention, said bowl portion is formed exteriorly at its upper edge with a circumferential groove 7 for a purpose hereinafter more fully described.

50 My improved cleaner constitutes the provision of a single strip of relatively narrow and thin sheet metal, preferably of aluminum, 8, that is bent into general U-shape as formed. The legs and connecting portion of this U-shaped member are adapted to have close contact with the interior

of the bowl in order that the edges thereof will scrape from the interior any matter that may collect thereon during the operation of the cleaner. The U-shaped strip is secured 60 for rotation within the bowl through the medium of a rivet 9 that passes through the connecting portion and bottom wall of the bowl, as shown.

The upper ends of the legs 8 of the U-shaped cleaner strip are formed with laterally extending portions 10-10 that engage over the upper edge of the bowl and that are formed with downwardly extending and inwardly bent portions 11-11, 12-12, 70 that engage the side of the bowl and within the circumferential groove 7 for preventing any wobbling of the cleaner upon its pivot 9 which would otherwise impair the efficient operation of the device, the portions 75 12-12 engaging within the grooves preventing any tendency of the side legs of the cleaner member 8 from disengaging the interior surface of the bowl during the cleaning operation.

In the form of the invention shown in Figures 2 and 3, the pipe bowl 5' is formed at its upper end with internal threads 13 and adapted for threaded insertion within the bowl and preferably in spaced relation to the lower portion thereof is an auxiliary bowl 14 of suitable sheet metal that is of the general shape of the pipe bowl 5', and that is formed at its upper edge with a flange 15 for close engagement with the upper edge 90 of the bowl for limiting the inner threaded engagement of the auxiliary bowl 14 with the pipe bowl 5'.

In this form of the invention, the cleaner element 8' is also formed from a single 95 length of sheet metal being bent into U-formation, for association within the auxiliary bowl 14, the lower connecting portion thereof being swivelly connected to the bottom of the auxiliary bowl through the medium of a rivet 16, in order that the cleaner may be freely rotated within the bowl for cleaning the side walls thereof after each smoke.

The upper ends of the legs of the cleaner 100 8' are extended outwardly over the auxiliary bowl flange 15 as at 10'-10', and then downwardly and inwardly at 12'-12' for engagement within a rabbet formed at the perimeter of the under side of the auxiliary bowl flange 15, for similar purposes to the 110 like construction of the form shown in Figure 1.

In this form of the invention, the portions 10'-10' of the U-shaped cleaner element 8' are formed with struck up pairs of lugs or ears 16 and 17. Between the lugs or ears 16 and 17 are similar struck up lugs or ears formed upon the extension 19 of a disk-shaped cover 20 for the auxiliary bowl 14, said disk-shaped cover being formed with a 10 tongue 21 in opposed relation with the extension 20 for frictional engagement between the ears or lugs 17 for maintaining the cover in closed position.

The vertical lugs of the portions 10-10' of the cleaner 8, shown in Figure 1, provide finger engaging elements whereby the cleaner may be turned about its axes in the cleaning of the bowl, while the ears or lugs 16 and 17 of the form of the invention shown in 20 Figures 2 and 3 are provided also for this additional function, and it will readily be understood that I have provided a highly novel and efficient form of cleaner that may be associated with a multiplicity of pipe constructions without materially altering the same.

My improved cleaner may be adapted for other pipe constructions than those shown in the drawings, and also minor changes 30 may be made in the invention per se without departing from the spirit and scope of the appended claims.

Having thus described my invention, what I claim as new and desire to secure by Letters Patent is:

1. In a cleaner for smoking pipes provided with a removable auxiliary bowl, a U-shaped metallic strip adapted for insertion within the auxiliary bowl, a pivotal connection between the lower portion of the 40 U-shaped strip and the bottom wall of the auxiliary bowl for facilitating the movement of the strip within the bowl, and a cover for the auxiliary bowl in the form of a disk that has pivotal connection with the 45 upper end of one of the legs of the U-shaped member.

2. In a cleaner for smoking pipes provided with a removable auxiliary bowl, a U-shaped metallic strip adapted for insertion within the auxiliary bowl, a pivotal connection between the lower portion of the 50 U-shaped strip and the bottom wall of the auxiliary bowl for facilitating the movement of the strip within the bowl, a cover for auxiliary bowl in the form of a disk that has pivotal connection with the upper end of one of the legs of the U-shaped strip, and means carried by the upper end of the 55 other leg of the U-shaped strip whereby the cover disk may be maintained in closed position.

In testimony whereof I affix my signature.
FRANK F. WEBER.
